(57) **CLAIM**

We claim the ornamental design for a identification tag, substantially as shown and described.

DESCRIPTION

FIG. 1 is a frontal elevation view of the identification tag; FIG. 2 is a right side view of the FIG. 1 identification tag, the left side view being the same;

FIG. 3 is a rear elevation view of the FIG. 1 identification tag;

FIG. 4 is a lower end view of the FIG. 1 identification tag; and,

FIG. 5 is a top end view of the FIG. 1 identification tag.
